UNITED STATES PATENT OFFICE.

FREDERICK WILLSON, OF READING, PENNSYLVANIA, ASSIGNOR TO T. A. WILLSON & CO., INC., OF READING, PENNSYLVANIA, A CORPORATION OF PENNSYLVANIA.

DESIGN FOR A NOSE BRIDGE-AND-BRACE PIECE FOR SPECTACLES.

52,123.

Specification for Design.

Patented June 18, 1918.

Application filed April 17, 1918. Serial No. 229,209. Term of patent 14 years.

To all whom it may concern:

Be it known that I, FREDERICK WILLSON, a citizen of the United States, residing at Reading, in the county of Berks and State of Pennsylvania, have invented a new, original, and ornamental Design for a Nose Bridge-and-Brace Piece for Spectacles, of which the following is a specification, reference being had to the accompanying drawing, forming part thereof.

The drawing shows a front view and a top view of a nose bridge-and-brace piece for spectacles showing my new design.

I claim:

The ornamental design for a nose bridge-and-brace piece for spectacles as shown.

In testimony whereof I affix my signature.

FREDERICK WILLSON.
